SIMULATED HEADLIGHT FOR TOY VEHICLES OR THE LIKE

Harry Golden, New York, N.Y., assignor to Ideas for
Auto and Bike Specialties, Inc., New York, N.Y., a
corporation of New York

Filed May 6, 1966, Ser. No. 2,202

Term of patent 14 years

(Cl. D34—15)

FIGURE 1 is a front elevational view of a simulated headlight for toy vehicles or the like embodying my new design;

FIGURE 2 is a sectional view thereof taken along the line 2—2 of FIGURE 1;

FIGURE 3 is a sectional view thereof taken along the line 3—3 of FIGURE 1;

FIGURE 4 is a side elevational view thereof;

FIGURE 5 is a rear elevational view thereof; and,

FIGURE 6 is a perspective view showing the manner in which a pair of such headlights are applied to the fenders of toy vehicles, the dotted line illustrations of the toy vehicle and headlight being for illustrative purposes only.

The characteristic features of my design reside in the particular arrangement of reflective pockets along the convex front surface, as shown in FIGURES 1, 2 and 3.

I claim:

The ornamental design for a simulated headlight for toy vehicles or the like, as shown and described.
